Robert E. Iannini, Milford, N.H., assignor to Rid-O-Ray
Inc., Milford, N.H.

Filed May 17, 1971, Ser. No. 144,397

Term of patent 14 years

Int. Cl. D26—03; D22—06
U.S. Cl. D48—31

FIG. 1 is a side elevational view of a combined lantern and insect killer and post therefor embodying my new design, the opposite side being a mirror image thereof;

FIG. 2 is a front elevational view;

FIG. 3 is a rear elevational view;

FIG. 4 is a top plan view; and

FIG. 5 is a bottom plan view thereof.

The post is broken away to indicate indeterminate length.

I claim:

The ornamental design for a combined lantern and insect killer and post therefor, substantially as shown and described.
